UNITED STATES PATENT OFFICE.

CHARLES S. MERRITT, OF DETROIT, MICHIGAN, ASSIGNOR OF ONE-THIRD TO ANDREW McCALLUM AND ONE-THIRD TO JOHN O'NEIL, BOTH OF DETROIT, MICHIGAN.

WRENCH.

1,199,806.

Specification of Letters Patent.

Patented Oct. 3, 1916.

Application filed May 16, 1916. Serial No. 97,964.

To all whom it may concern:

Be it known that I, CHARLES S. MERRITT, a citizen of the United States of America, residing at Detroit, in the county of Wayne 5 and State of Michigan, have invented certain new and useful Improvements in Wrenches, of which the following is a specification, reference being had therein to the accompanying drawings.

10 This invention relates to a quick acting wrench, and the objects of my invention are, first, to provide a wrench having a novel adjusting mechanism that can be easily and quickly manipulated to permit of the adjustable jaw of the wrench being shifted to a desired position upon the shank of the wrench; second, to provide a strong and durable wrench having the adjusting means thereof housed and partly concealed where- 20 by the wrench may be roughly handled without any danger of the adjusting mechanism being injured; third, to provide a wrench of the above type that can be advantageously used as a nut or pipe wrench and particu- 25 larly as a tool for an automobile or bicycle kit, and fourth, to provide an inexpensive wrench consisting of comparatively few parts that can be easily and quickly assembled.

30 The above and other objects are attained by a mechanical construction that will be hereinafter specifically described and then claimed, and reference will now be had to the drawing, wherein—

35 Figure 1 is a view of one side of the wrench; Fig. 2 is a similar view of the opposite side thereof, showing the shank partly broken away; Fig. 3 is a cross sectional view of the adjustable jaw of the 40 wrench; Fig. 4 is a side elevation of a portion of the wrench showing the adjustable jaw thereof in longitudinal section; Fig. 5 is an enlarged perspective view of a detached gripping member, and Fig. 6 is a 45 side elevation of a portion of a wrench provided with pipe gripping jaws.

In the drawing, 1 denotes a comparatively flat shank, preferably rectangular in cross section, and having the outer end thereof 50 provided with a fixed jaw 2. The front side of the shank 1 has ratchet teeth 3 contiguous to the outer end of the shank, and the inner end of the shank constitutes a handle by which the wrench may be conven- 55 iently manipulated.

Slidable upon the shank 1 is an adjustable jaw body 4 having a jaw 5 confronting the fixed jaw 2 of the shank 1, these jaws being designed for gripping the facets of the nut although said jaws may have the 60 confronting faces thereof concave and serrated, as indicated at 6 in Fig. 6, whereby a wrench in accordance with my invention may be utilized for rotating pipes or structures having curvilinear surfaces. The adjustable jaw body 4 has a longitudinal opening 7 to receive the shank 1 and one side of the body 4 has a transverse slot 8 communicating with a recess 9 in the body 4.

The slotted side of the body 4 is provided with an offset guide or boss 10 closing a portion of the slot 8 and slidable in the slot 8 and the guide 10 is a gripping member 11 provided with right angular disposed ends 12 and 13. The end 12 of the gripping member extends into the recess 9 of the body 4 and is toothed, as at 14, to engage the teeth 3 of the shank 1. In the recess 9 is a coiled compression spring 15 bearing against the end 12 of the gripping member and the expansive force of this spring holds the toothed end of said gripping member normally in engagement with the teeth 3 of the shank 1, thereby holding the adjustable jaw body 4 against movement in one direction 85 upon the shank, until the gripping member is shifted out of engagement with said shank.

The end 13 of the gripping member is disposed in parallelism with the back of the adjustable jaw body 4, and is preferably formed with a serrated concavity affording a finger or thumb seat which permits of the gripping member 11 being easily shifted by the thumb or finger of a hand gripping the shank 1.

With the ratchet teeth 3 of the shank 1 disposed in the manner shown in Fig. 1, the adjustable jaw body 4 can be easily shifted toward the fixed jaw 2, as the toothed end 12 of the gripping member 11 recedes over the teeth. Should it be desired to move the adjustable jaw body away from the fixed jaw 2, it is only necessary to press inwardly upon the gripping member 11 to move the toothed end 12 thereof into the recess 9 and out of engagement with the toothed shank 1, at which time the adjustable jaw body can be shifted upon the shank. When the gripping member 11 110

is released, the spring 15 places the toothed end of the gripping member in engagement with the shank, thus preventing the adjustable jaw body from slipping while the wrench is being used.

With the gripping member 11 countersunk in the adjustable jaw body 4 and the upper and lower edge thereof guided by the walls of the slot 8, it is practically impossible for the gripping member to become accidentally displaced and the offset guide 10 on the side of the adjustable jaw body retains the gripping member in the slot of the jaw body and protects that end 15 of the gripping member extending into the recess 9. The guide 10 is welded upon the side of the adjustable jaw body, and the gripping member is placed in position and with the parts assembled in this manner the 20 adjustable jaw can be easily removed from the shank and easy access had to the recess 9.

What I claim is:—

In a wrench, the combination with a shank having a fixed jaw, of a jaw body 25 slidable upon said shank and provided with a single recess and a side slot, said slot extending from the back of said jaw body

to a point approximately central of the side wall of said jaw body to communicate with the recess thereof, an outstanding guide on 30 one side of said jaw body of less breadth than said shank and closing the recess communicating end of the slot of said jaw body, a one-piece gripping member slidable in the slot of said jaw body and said guide and having angularly disposed ends, with one end of said gripping member toothed and corresponding in width with said shank, and extending into the recess of said jaw body to engage said shank, the opposite 35 end of said gripping member being in spaced relation to the back of said adjustable jaw body and providing a concave finger piece, and means in the single recess of said jaw body adapted to hold the toothed end of 40 said gripping member normally in engagement with said shank.

In testimony whereof I affix my signature in the presence of two witnesses.

CHARLES S. MERRITT.
